Thomas Shaw

United States Patent Office.

THOMAS SHAW, OF PHILADELPHIA, PENNSYLVANIA.

Letters Patent No. 98,430, dated December 28, 1869.

IMPROVEMENT IN MACHINES FOR PRESSING CLAY PIPES.

The Schedule referred to in these Letters Patent and making part of the same

To all whom it may concern:

Be it known that I, THOMAS SHAW, of the city and county of Philadelphia, Pennsylvania, have invented a new and improved Machine for Pressing Clay Pipe; and I hereby declare, the following to be a full, clear, and exact description of the same, reference being had to the accompanying drawings, and to the letters of reference marked thereon.

My invention consists in a machine for employing liquid, gas, or steam-pressure in the same tub in which the clay is placed, in the manner and for the purpose as hereafter described.

In order to enable others to use and practise my invention, I will proceed to describe its construction and operation.

On reference to the accompanying drawing, which forms part of the specification—

Figure 1 represents a front view of the machine, and

Figure 2 represents a transverse view of a vertical section through the centre of machine.

Similar letters refer to similar parts, of which—

p is a bed-plate, resting upon three pillars, *h*, upon which rests tub *b*, provided with cover *k*.

Said cover *k* has an annular recess at *r*, and the tub *b* has a corresponding projecting rib, fitting into the same.

Said rib and annular recess are cut out in alternate lengths of distance, that said cover may be made fast or loose from the tub, by revolving the same slightly, when desiring to secure or loose the same.

A gum or other suitable packing-ring may intervene between the cover and tub, for the purpose of securing a tight joint.

a are pillars, secured to base *p* and beam *d*.

c is a hollow rod, secured to beam *d*, and passes through a stuffing-box in cover *k*, and through a follower, *m*, and has a die secured to its lower end, *n*.

l is a disk, held loosely in its centre by an annular recess formed in follower *m*, that the disk and follower may revolve independently of each other.

f are two rods, secured to said disk, and pass through stuffing-boxes in cover *k*, and are united at the top by means of a cross-bar, *g*, provided with a ring in its centre, to enable the hoisting of the same.

e is an inlet-pipe, communicating with hollow rod *c*.

i is an outlet-aperture, all for the purpose as hereafter described.

o is a female die, for the purpose as hereafter described.

The press is operated in this wise:

The cover *k* is turned so as to be released from tub *b*, when an ordinary hoisting-appliance, the rope of

which is fastened to ring *g*, lifts the rods *f* and follower *m* until the follower comes in contact with the cover *k*, when that is also lifted, together with the follower, as high as the beam *d* will permit, at which time the tub *b* is empty, and ready for the load of clay, which is thrown in, and packed tightly, (to the capacity of the tub,) when the follower is lowered down, and pressed upon the same, when the cover *b* is locked fast to the tub. At this period, steam, air, or water-pressure can be applied by connecting a pipe, conveying the same, with tube *e*, conveying the fluid into hollow rod *c*, and has exit from an aperture above the follower, at *i*.

The pressure of the fluid is exerted over the whole area of the follower, forcing it down, and the clay beneath it out at the opening at the bottom of the tub *b*, and around the disk *l*, which operation is continued until nearly all the clay is forced out of the tub in the shape of pipe, which is cut off in suitable lengths, at the will of the operator, by the ordinary wire cutting-appliance.

When all the clay is forced out that is desired, the follower and cover are lifted, that the tub may be refilled with clay, as before described.

This apparatus is also so arranged that the power may be applied directly upon the clay, thus dispensing with expensive steam and hydraulic cylinders, and their costly appliances, and causes the tub to act at once as steam-cylinder and tub.

It will be observed that the pressure of fluid can as readily be applied by tapping one side of the upper part of the tub as through the hollow rod *c*; and that various shapes and sizes of dies can be placed at the bottom of the tub; and that various other methods can be used to secure the cover *k* to the tub; and that, in the pressing of certain-sized pipe, the follower may be dispensed with entirely, without any alteration in the result. I therefore do not wish to confine myself to the precise shape of the apparatus; but

What I do claim, and desire to secure by Letters Patent, is—

1. The pipe-press herein described, consisting of the tub *b*, cover *k*, disk *l*, with rods *f*, and hollow rod *c*, with its inlet *e* and outlet *i*, when constructed and operated in the manner and for the purpose herein set forth.

2. In connection with the above-named parts, the piston *m*, when constructed and combined with said parts, as and for the purpose herein set forth.

THOMAS SHAW.
